UNITED STATES PATENT OFFICE.

WALTER B. SWINDELL, OF BALTIMORE, MARYLAND.

DESIGN FOR A BOTTLE.

SPECIFICATION forming part of Design No. 31,518, dated September 19, 1899.

Application filed August 22, 1899. Serial No. 728,132. Term of patent 7 years.

To all whom it may concern:

Be it known that I, WALTER B. SWINDELL, a citizen of the United States, residing in the city of Baltimore, State of Maryland, have ⁵ invented a certain new and useful Design for a Bottle, of which the following is a specification.

My design for a bottle is fully shown in the accompanying drawings.

10 In the drawings, Figure 1 is a side view of a bottle embodying my design. Fig. 2 is a bottom plan view thereof. Fig. 3 is a cross-section thereof on the line 3 3, Fig. 1.

The essential feature of the design consists ¹⁵ in a bottle shaped substantially as shown in the drawings.

Referring to the drawings, 1 is the body of the bottle, which is formed of six straight plane faces 2 and 7, the former constituting ²⁰ panels in opposite faces of the bottle, while the latter form the sides of the body and extend from said panels on each side at equal angles and are joined by curved surfaces 8,

forming rounded edges. These edges and the front and rear of the bottle extend from the ²⁵ rounded shoulder in parallel directions toward the base 6, to which they are joined by graceful and easy curves 9, said base being of elliptical shape, and similarly the sides, the rear, and front of the body of the bottle ³⁰ merge into and form a symmetrically-curved shoulder, above which is a rounded bead 4 at the base of the neck 3, the top or mouth being surrounded by a similar bead 5.

Having thus described my invention, what ³⁵ I claim, describe, and desire to secure by Letters Patent is—

The design for a bottle, substantially as shown and described.

In testimony whereof I have signed my ⁴⁰ name to this specification in the presence of two subscribing witnesses.

WALTER B. SWINDELL.
